UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLER.

Application filed November 4, 1924. Serial No. 747,810.

To all whom it may concern:

Be it known that I, WILLIAM KELSO, a citizen of the United States, residing at Pittsburgh, in the county of Allegheny and State of Pennsylvania, have invented certain new and useful Improvements in Car Couplers; and I do hereby declare the following to be a full, clear, and exact description of the invention, such as will enable others skilled in the art to which it appertains to make and use the same.

My invention relates to car couplers and more particularly to the locking mechanism whereby the knuckle of the coupler is normally restrained from performing an unlocking rotation.

The principal object of the invention is to provide simple and efficiently operating and easily assembled mechanism for operating the coupler lock and for preventing it from accidentally moving to an unlocked position.

A primary feature of the invention consists in pivotally mounting upon the coupler lock a device adapted to prevent the latter from accidentally moving to unlocked position, and in combining therewith an uncoupling member which is provided with an elongated opening through which a portion of the lock extends, the said lock and the device movably mounted thereon being adapted to interlock with the uncoupling member when the latter is in assembled position, and the said uncoupling member being capable of being disassembled from the lock only after it has been brought to a position not normal to its operation.

A further and more specific feature of the invention consists in forming the lock of a car coupler with a lug which projects downwardly through an opening in the coupler head, pivotally mounting upon said lug below said head a device for preventing the lock from accidentally moving to unlocked position, and combining therewith an uncoupling member adapted to actuate said pivotally mounted device and subsequently causing an unlocking movement of the lock, the said uncoupling member having a portion extending between spaced lugs, one of said lugs being upon the pivoted device and being adapted to be engaged by the uncoupling member, and the other lug being car-

ried by the lock and being adapted to furnish support for the uncoupling member. 55

Other features of the invention, residing in advantageous structural forms and particular relations of parts will hereinafter appear and be pointed out in the claims.

In the drawings illustrating the invention,—

Figure 1 is a transverse sectional view of a car coupler embodying the invention, a portion of the uncoupling member for actuating the locking mechanism being broken away and the parts being in locked position. 65

Figure 2 is a detail view corresponding to Fig. 1, but illustrating the relative positions of the parts when the lock has been freed from the control of the lock-to-the-lock device. 70

Figure 3 is a detail view in side elevation of a portion of the locking mechanism, the relation of the uncoupling mechanism thereto being indicated in dotted lines. 75

Figure 4 is a detail view corresponding to Fig. 3, but showing this portion of the mechanism in rear elevation.

Figure 5 is a detail sectional view on the line 5—5, Fig. 1. 80

Figure 6 is a view corresponding to Fig. 1, but illustrating a modified form of the invention.

Figure 7 is a detail view of a portion of the construction shown in Fig. 6, but illustrating the lock-to-the-lock member as having been actuated to permit the lock to perform an unlocking movement. 85

Figure 8 is a detail view in side elevation showing a portion of the modified form of locking mechanism. 90

Figure 9 is a view in rear elevation of the parts shown in Fig. 8.

Figure 10 is a sectional view on the line 10—10, Fig. 7. 95

The coupler is of the well known Master Car Builders' type having a head 1 upon which is pivotally mounted a knuckle 2. Outward rotation of the knuckle is normally prevented by a lock 3 which, in the present instance, is shown as being adapted to actuate a bell crank knuckle opener 4 housed within the coupler head. 100

As shown in Figs. 1 to 5, inclusive, the lock 3 is provided with a leg 5 which extends downwardly through an opening 6

in the under side of the coupler head. Pivotally mounted upon the lock leg 5 is a member 7, or lock-to-the-lock device, which cooperates with the coupler head to prevent the lock 3 from accidentally moving to unlocked position. For the purpose of pivotally connecting the member 7 to the lock leg 5 the latter may be slotted or recessed at its lower end, as indicated at 8, for the reception of the rounded lower end of the lock-to-the-lock member, a pin or rivet 9 which passes through both of said members serving as a pivot. At its upper end the member 7 is preferably stepped so as to provide a shoulder 10 adapted to stand beneath a portion 11 of the coupler head and thus lock the lock 3 against an accidental unlocking movement. The portion 12 of the member 7 which is above the shoulder 10 and projects into the opening 6 in the coupler head, serves, by engaging the said head, to limit the extent of swinging movement of the lock-to-the-lock device 7 away from the lock 3. Pivotal movement of the member 7 in the opposite direction may conveniently be limited by forming the leg 5 of the lock with a face or shoulder 13 with which said member 7 is adapted to contact at the end of its lock releasing movement. At one side and somewhat above its pivotal point 9 the member 7 is preferably fashioned with oppositely extending lugs 14 which are adapted to be engaged by the uncoupling member 15 when the inner end of the latter moves upwardly in the performance of an uncoupling operation. By this construction the initial movement of the uncoupling member results in causing the shoulder 10 of the pivoted member to be withdrawn from beneath the cooperating portion 11 of the coupler head, as illustrated in Fig. 2.

Below the pivotal point of the lock-to-the-lock device 7 the lock leg 5 may advantageously be provided with a plurality of oppositely extending lugs 16 furnishing support for the inner end of the uncoupling member 15 when the latter is in normal position corresponding to the locked relation of the coupler parts. The portion of the lock leg 5 which is immediately above the supporting lugs 16 is somewhat reduced in size and preferably is of cylindrical form; and the inner end of the uncoupling member 15 is provided with an elongated opening or eye 17 for receiving and interlocking with this portion of the locking mechanism. The elongated form of the eye 17 permits the lugs 16 at the lower end of the lock leg 5 to pass therethrough when the uncoupling member is turned at right angles to its normal assembled position, but as shown in Figs. 3 and 5, the lugs 16 support the inner end of the uncoupling lever and retain it in assembled relation to the lock when the parts are in normal position.

The modified embodiment of the invention illustrated in Figs. 6 to 10, inclusive, differs from the construction heretofore described only in respect to details of the depending lock leg and the lock-to-the-lock member pivotally mounted thereon. In this form the downwardly extending leg 18 of the lock 3, instead of being provided with two oppositely extending lugs 16 for the support of the uncoupling member 15, is provided with only one such lug, the other being in effect provided by a lug 19 formed on the lock-to-the-lock member 20. The upper surface of the lug 19 is preferably beveled so as to permit the member 20 to pivot readily when the weight of the uncoupling member rests thereon. The member 20 is provided with an integrally attached trunnion or pintle 21 which enters a corresponding pivot opening 22 in the lock leg 18 and thereby forms a pivotal mounting for the lock-to-the-lock device. Other features of construction illustrated in Figs. 6 to 10 are substantially identical in form to those heretofore described and they have accordingly been indicated by corresponding reference characters.

When the uncoupling member or lever 15 is manipulated so as to cause its inner end 17 to move upwardly, the sides of its eye portion come into contact with the lugs 14 upon the lock-to-the-lock member 7, thus causing the latter to rotate upon its pivot 9 until its locking shoulder 10 has been withdrawn from beneath the cooperating shoulder 11 of the coupler head. Further upward movement of the inner end of the uncoupling member 15 then causes the lock to perform an unlocking operation. When the lock 3 drops to unlocked position the lock-to-the-lock member automatically swings to locked position under the influence of gravity, its shoulder 10 assuming a position beneath the cooperating portion 11 of the coupler head. In this position of the parts the inner end of the uncoupling member 15 is supported upon the lugs 16 of the locking mechanism.

The operation of the modified form of construction shown in Figs. 6 to 10, inclusive, is the same as that just described except that the return of the lock-to-the-lock member 20 to locked position and its retention in such position are assisted by the imposition of the weight of the uncoupling member 15 upon the lug 19 with which said member 20 is provided.

I claim:

1. A car coupler having a head, a knuckle, a lock for said knuckle, a device for preventing said lock from accidentally moving to unlocked position, and means for actuating said device to permit said lock to move to unlocked position, said means being adapted to effect an unlocking movement

of said lock through the intermediary of said device and being supported by said lock when the latter is in locked position, said device being pivotally mounted on said lock 5 beneath said head and having a shoulder adapted to engage a portion of said head to prevent accidental unlocking of said lock, and said device also being provided with a lug adapted to be engaged by said means to cause said device to execute a pivotal movement with respect to said lock, said lug serving to limit upward movement of said means with respect to said lock.

2. A car coupler having a head, a knuckle, 15 a lock for said knuckle, a device pivotally mounted on said lock and adapted to engage said head to prevent said lock from accidentally moving to unlocked position, and means for actuating said device to permit said lock to move to unlocked position, said lock and the device pivotally mounted thereon being constructed to provide a plurality of vertically spaced lugs between which said actuating means extends, said 20 lugs serving as stops for limiting movement of said actuating means with respect to said lock, and one of said lugs being adapted to be engaged by said actuating means to cause said pivotally mounted device to move to 25 a position permitting an unlocking movement of said lock.

3. A car coupler having a head, a knuckle, a lock for said knuckle, a device movably mounted on said lock and adapted to prevent 35 the latter from accidentally moving to unlocked position, and means for actuating said device and said lock, said means having a portion embracing said lock and said device movably mounted thereon.

4. A car coupler having a head, a knuckle, a lock for said knuckle, a device movably mounted on said lock and adapted to prevent the latter from accidentally moving to unlocked position, and means for actuating said 45 device and said lock, said means being provided at one end with an elongated opening through which a portion of said lock extends, and said lock and said device movably mounted thereon being adapted to interlock with said means when the latter is in assembled position.

5. A car coupler having a head, a knuckle, a lock for said knuckle, said lock being movable to locked position under the influence 55 of gravity and having a leg projecting downwardly through an opening in said head, a device pivotally connected to said leg below said head and adapted to prevent said lock from accidentally moving to unlocked position, and an uncoupling member adapted to effect a pivotal movement of said device with respect to said lock and a subsequent unlocking movement of said lock, said uncoupling member being operatively interposed between spaced lugs, one of said lugs

being upon said pivoted device and being adapted to be engaged by said uncoupling member, and the other lug being upon said leg of the lock and being adapted to support said uncoupling member. 79

6. A car coupler having a head, a knuckle, a lock for said knuckle having a leg projecting downwardly through an opening in the coupler head, a device pivotally mounted on said leg below said head and adapted to engage said head to prevent said lock from accidentally assuming an unlocked position, and an uncoupling member for successively actuating said device and said lock, said lock being provided with a shoulder 85 forming a stop for limiting pivotal movement of said device and having a lug forming a support for said uncoupling member, and said pivotally mounted device being provided with a lug adapted to be engaged by said uncoupling member when the latter is operated to effect an unlocking movement of the said lock.

7. A car coupler having a head, a knuckle, locking means for said knuckle, and an uncoupling member for actuating said means, said uncoupling member being provided with an opening through which said locking means extends, said locking means being provided with a plurality of lugs forming 90 a support for said uncoupling member when the parts are in locked relation, and said locking means and uncoupling member being adapted to be disassembled only after said uncoupling member has been caused 95 to assume a position permitting said lugs to pass through said opening.

8. A car coupler having a head, a knuckle, locking means for said knuckle, and an uncoupling member for actuating said means, said uncoupling member being interlockingly connected to said locking means and being provided with an opening through which said means extends, said locking means being provided with a plurality of lugs spaced 105 vertically to receive said uncoupling member between them, certain of said lugs forming a support for said uncoupling member when the parts are in locked relation, and said locking means and uncoupling member being adapted to be disassembled only after said uncoupling member has been caused to assume a position permitting said last named lugs to pass through said opening. 110

9. A car coupler having a head, a knuckle, a lock for said knuckle having a leg projecting downwardly through an opening in said head, said leg being provided with a lug adapted supportingly to engage an uncoupling member, a device pivotally connected to said leg above said lug for preventing said lock from accidentally moving to unlocked position, and an uncoupling member adapted to actuate said device and subsequently to actuate said lock 120 125 130

through the intermediacy of said device, said device being provided with a lug adapted supportingly to engage said uncoupling member and also being provided with oppositely disposed lugs constituting means whereby said uncoupling member is adapted to actuate said pivoted device.

10. A car coupler having a head, a knuckle, a lock for said knuckle having a leg projecting downwardly through an opening in said head, a member pivotally mounted on said leg and adapted to cooperate with said head to prevent said lock from accidentally moving to unlocked position, and an uncoupling member for causing the successive operation of said pivotally mounted member and lock, said uncoupling member being provided with an opening receiving the lower end of said leg, said leg being provided with lug means forming a support for said uncoupling member, and said pivotally mounted member being provided above its pivotal point with lug means adapted to be engaged by said uncoupling member when the latter performs an uncoupling operation.

11. A car coupler having a head, a knuckle, a lock for said knuckle having a leg projecting downwardly through an opening in said head, said leg being provided with a lug adapted to form a support for an uncoupling member, a member pivotally mounted on said leg and adapted to cooperate with said head to prevent said lock from accidentally moving to unlocked position, said pivotally mounted member being adapted to enter said head through said opening and being provided above its pivotal point with oppositely extending lugs and also having a lower lug adapted to form a support for an uncoupling member, and an uncoupling member having an elongated eye receiving said leg and the member pivotally mounted thereon, said uncoupling member being adapted to engage said oppositely extending lugs of said pivoted member and normally being supportingly engaged by said lug of the lock leg and said lower lug of said pivoted member.

In testimony whereof I affix my signature.

WILLIAM KELSO.
